UNITED STATES PATENT OFFICE.

JAMES H. GAULT, OF PHILADELPHIA, PENNSYLVANIA.

CARD-PUNCHING MACHINE.

Application filed June 9, 1920. Serial No. 387,596.

To all whom it may concern:

Be it known that I, JAMES H. GAULT, a citizen of the United States, residing at the city of Philadelphia, in the county of Philadelphia and State of Pennsylvania, have invented certain new and useful Improvements in Card-Punching Machines, of which the following is a specification.

The present invention relates to a punching machine for simultaneously making a plurality of perforations in a blank while the range or capacity for variations of the punch control is under the selective influence of a perforated master or pattern card, though as will be hereafter shown, other automatic means of influence may replace such master card and, for some kinds of work, the machine may be placed under the selective or governing influence of an operative.

The embodiment of the invention herein set forth is more particularly adapted to register on a tabulating card by means of perforations, statistical data automatically taken from another card in which such data has been previously punched as is done in the compilation of many forms of commercial, scientific and governmental data, such as municipal, State and national statistics, tabulation of census returns, etc.

The functions of the invention are not confined to this field alone, nor its principles to the embodiment herein set forth. The very broad and exacting requirements of the tabulating art demand a practically universal card punching machine and this art is therefore best suited to illustrate the wide range and great flexibility of the invention.

The invention is, however, equally, applicable to any of the arts requiring card perforation, a notable example being the production of perforated Jacquard loom cards. In the various ramifications of the loom card perforating art, a variety of work is required which, in the present state of that art, requires several distinct types of machines, some with cumbrous attachments which in a limited way increase their normally narrow range. The universal range and great flexibility of the present invention enables it to perform all the various sorts of work done by these different types of machines and also produce a great variety

of designs from a single set of pattern cards without special attachments.

Thus in the production of jacquard cards it may be used to make the master cards themselves, and it may be used as a repeater to duplicate master cards or to punch cards with any desired variation from the operating master card, either by the omission or addition of any desired hole or group of holes or by any change in the relative positions of any of the holes. It will also punch the negative or reverse card and can be readily adapted to punch cards under the influence of a movable electrically conductive pattern surface, in co-operation with contact styles or needles.

Specifically the objects of the present embodiment of the invention are to provide for automatically punching a tabulating card under the selective influence of a master card so that various items of data registered by perforations in the master card will be transferred to the card being punched, the relative positions of the perforations on the two cards being the same or differing in any manner desired according as the data spaces printed on the two cards are similarly located or are in different relative arrangement; to provide for automatically selecting a desired portion only of the data registered by perforations on the master card and registering it by perforations in any desired positions on the tabulating card, omitting all else; to provide for registering by perforations on the tabulating card additional or later data not perforated on the influencing master card; to provide for verifying any tabulating card punched by immediately afterward punching a complementary card, that is, a card which has all possible perforations except those in the master card. This verification may be done either continuously or intermittently as desired; to provide for automatically selecting from a mass or stack of master cards any group or groups of related cards and punching tabulating cards corresponding to these groups only, registering thereon all the data perforated in the required groups or only selected portions of such data as desired; to provide for punching a card under the selective skill of an operative reading from a written record or drawn design; to provide

for accommodating varying sizes of master cards and any variety of grouping or pattern of arrangement of data spaces on the master card, so that such grouping may exactly correspond with or differ in any or every way from that printed on the tabulating card to be punched; to provide for controlling the punches of the machine by a movable, electrically conductive pattern surface co-operating with contact styles; to provide for automatically feeding the master cards to and withdrawing them from the machine; to provide for automatically feeding the blank cards to the machine for perforation and withdrawing them after they have been punched; to provide for stacking the tabulating cards after their discharge from the machine.

To accomplish these ends the novel combination and arrangement of parts, improvements and original instrumentalities, which, together constitute the invention as a whole, have been evolved and are herein illustrated and described.

In the accompanying drawings Figure 1 is a side elevation of a machine embodying the invention. Figure 2 is a vertical longitudinal section of the upper portion of the machine by a plane indicated by $\alpha-\alpha$ in Figure 3. Figure 3 is a corresponding front elevation with some of the parts removed and others partly cut away. These two drawings together show the novel method of arranging or grouping the magnets in batteries of staggered rows so that the large number of very closely grouped punches may be directly controlled by magnets with little intervening mechanism. Figure 4 is a diagrammatic view illustrating the principles of the electric circuit system, including some of the operating elements of the machine. Figure 5 is a fragmentary side view of the rear end of the machine illustrating the means by which the electric currents are automatically shifted. Figure 6 is a side elevation of the mechanism for feeding the blank cards to the machine and removing them therefrom after perforation. Figure 7 is a plan view of this mechanism. Figure 7^A is a detail of said mechanism. Figure 8 is a front view of the contact board of the contact needle box or case. Figure 9 is an end elevation of the contact needle box. Figure 10 is an elevation of a portion of the rear of the machine with the attachment or device containing the contact styles used when it is desired to use the machine with a movable, electrically conductive pattern. Figure 11 is an end view of the device shown in Figure 10. Figure 12 is an elevation of a face of the revolving prism used in feeding the master card to the contact board. Figure 13 is a sectional view of the interior of said prism by a plane indicated by $\alpha-\alpha$ in Figure 12. Figure

14 shows the method of depositing the master card in a receiving magazine as the revolving prism carries them away from the contact needle after they have operated.

The punch head of the machine keys and wires for locking the punches are of the standard form long used in most all machines for punching Jacquard loom cards by the action of a master card or pattern sheet on selective needles, and no originality is claimed for these particular features.

The requirements of the tabulating art, which gave rise to the present invention, however demand a very much more versatile and flexible machine than such machinery as has heretofore been used and in which the relation between each selective needle and its corresponding punch is either absolutely fixed or is capable of only a very limited variation by the application of complicated attachments which require time and skill to apply. The present invention, through the novel arrangement of mechanism, between the selective needles and punch locking means, is capable of enabling any selective needle to control any punch of the head so that the needles and keys may be connected up in any variety of ways or it may be arranged to make any needle neutral or inoperative if required, thus giving the machine a flexibility and capacity not approached by the means heretofore used in the card punching art.

In the general view Figure 1, 30 denotes the main body of the machine, while the superstructure consists of the hood, 31, covering the punch head, the outer covering, 32, of the key wire chamber and the case, 33, containing the punch controlling solenoids which extends both above and below the key wire chamber. The portion below the chamber extends down into the body of the machine, as indicated by dotted line, while the portion rising above the key wire chamber supports the main plug or switchboard, 9, and the auxiliary plug plate, 24. The interior of the punch head, the key wire chamber and the solenoid case are fully shown in Figure 2 and Figure 3.

As the master cards used in the tabulating art will in general be considerably larger than the cards to be punched, the rear end of the key wire chamber is in the present embodiment made considerably wider than the punch head of the machine, as indicated in Figure 3. This extension of width will not be necessary where the invention is applied to producing jacquard cards. The sliding frame, 34, supporting the mechanism for handling the master cards, straddles the rear end of the machine and is slidably mounted in ways on opposite sides of the widened portion of the machine, one leg of the frame in each way, as indicated in Figure 1 and Figure 3. This frame is re-

ciprocated back and forth in the ways by rocking arms, 35 and 36, Figure 1 and Figure 3, which are actuated by a crank, 37, and connecting rod, 38. The shaft on which the 5 crank, 37, is mounted being turned by motion communicated from the main shaft, 39, through the beveled gears, 40 and 41, the main shaft being driven by a pulley, 42, which communicates motion to the said 10 shaft, 39, through the beveled gears, 43 and 44. On the front end of this main shaft is an eccentric or cam 190, which oscillates the ram, 53, up and down to accomplish the perforation of the card. A considerable 15 portion of this driving mechanism is conventional and no claim of originality is made for it, but it is shown for the purpose of unity and clearness.

The master cards are pneumatically 20 drawn from a horizontal stack, 45, held in a magazine, 46, and carried on the rectangular faces of a square prism, 2, to the contact board, 73, which is the face of the contact 25 box, fully illustrated in Figure 8 and Figure 9. This hollow prism, 2, whose details are fully shown in Figure 12 and Figure 13, has its trunnions, journaled in the sliding frame, 34. Rigidly mounted on 30 one of its trunnions where said trunnion extends outside of its journal, is a four-toothed ratchet, 122, acted on by a pawl, 48, carried by an arm, 49, which is mounted on the trunnion beside the ratchet and free 35 to turn back and forth thereon. This rocking arm has pivoted to it one end of the link, 50, the other end of which is pivoted to a sliding block, 51, in a slide way on the side of the key wire case, and which is held 40 back against a stop, 52, at the end of its way by a stiff spring, 123. The object of this spring block is to allow a yield in the block, 51, so that the frame, 34, may be pushed back a short additional distance even 45 after the rocking arm, 49, has met its stop, 52, which is a set screw mounted in a boss on the side of the sliding frame, 34, and located so as to meet a projection on the rocking 50 arm, 49, to prevent further turning of said arm when it reaches a point that properly positions the faces of the prism, 2, during the time that the frame moves outward from the body of the machine.

Placed at a suitable distance back of the 55 machine on a suitable support is a magazine, 46, containing the master cards, 45. The end of this magazine facing the machine is open, the cards which closely fit the width of the magazine are prevented from being forced out of the open end by the presser, 56, by slight knife-edged projections, one on either side of the magazine and just within the open end. These projections extend a 60 very short distance over each end of the outermost card and prevent the cards from 65 being pushed out of the open end by the

presser, 47, which pushes the cards up against them. When the rearmost face of the feeding prism, 2, approaches and is pressed against the outermost card, the 70 pneumatic suction exerted on the card by the prism, means for which are shown in Figure 12 and Figure 13 and hereinafter described, acting as it does near the middle of the card, the ends of said card are free 75 to bend away from the prism as it leaves the magazine on its return toward the machine, with the middle of the card held close to the prism by suction, so that the shortening effect due to the bellying of the card 80 allows the ends to slip from under the knife-like projections and the card is carried off with the prism and the remainder of the stack comes up against the projections and is stopped.

The sliding ram for forcing the die and 85 card to be perforated up against the punches is indicated by 53. At the upper end of the ram is the bolster, 54, to which is suitably secured the perforating die, 55, and the 90 punch guide and stripper, 56, fixed at a suitable distance above the die. To the bolster, 54, is also secured the frame, 57, of the mechanism for feeding cards to and withdrawing them from the punches. On 95 this frame, 57, is supported the magazine, 58, for holding the cards previous to feeding. This mechanism is more fully shown in Figure 6 and Figure 7 and hereinafter described in detail, as is also the magazine, 59, 100 for receiving of cards as they come from the shute, 60, after perforation.

This feeding mechanism is actuated by the cam-groove, 61, acting on the slide, 62, and through connecting rods, 63, rocker arm, 64, and link, 65. The double lever, 66, actuated by the cam-groove, 67, operates the oscillating grid-frame, 70, shown in Figure 2, to withdraw the keys from over the punches by the arm which is connected with the link, 68. The other arm of this lever is 105 used to operate the sliding plate, 21, Figure 3 and Figure 4, as indicated by the drawings. In Figure 2, showing the interior of the punch head, key wire chamber and solenoids case, the arrangement of the gang of 110 punches, 18 etc., in the head, and their locking keys, 16, 16', 16'', etc., and key wires, 15, 15', 15'', etc., is the same as is usual in nearly 115 all forms of jacquard card punching machines. The punch locking keys are controlled by electromagnets of the solenoid type.

The peculiar method of arranging and 120 grouping the solenoids, 11, 11', 11'', etc., here illustrated, and made still plainer by 125 reference to Figure 3, although very simple, is of great merit as it affords a method of concentrating in a comparatively small space a sufficient number of solenoids to control the locking of the numerous, closely grouped 130

punches. This simple and direct method of connecting the key wires to the solenoids is an improvement over the complicated and tenuous mechanism heretofore used in the art for this purpose, and its novel conjunction with a plug-board, 9, for interchanging the contact needles between the solenoids, as hereinafter explained, gives a flexibility and variety of punch control which is not approached by the machines in present use. The solenoids, 11, 11', 11'', etc., are arranged in parallel groups or batteries on vertical supports or partitions, 69, 69', 69'', etc., in the solenoid case, 33 extending above and below the groups of key wires. The number of these batteries of solenoids is equal to the number of horizontal layers of key wires. Each battery is made up of a number of groups of magnets, each group arranged in a straight line, as A, B, C, etc., and secured to its support at such an incline to the horizontal as is best suited to admit of each individual magnet being properly connected to its corresponding key wire by a lever without interference, and at the same time enable the necessary number of magnets to act in a very limited space fixed by the closely grouped punches. The straight line groups or elements are arranged for space saving purposes in the staggered row, as will best be understood by reference to Figure 3.

In the present embodiment of the invention the upper horizontal layers of key wires are controlled through the levers, 14, 14', 14'', etc., by the batteries in the upper part of case, 33, above the key wire chamber, one battery controlling each horizontal layer. The said levers varying in length, each being of a length suitable to the distance of its controlling solenoid above the key wire it controls. These levers in the present embodiment are pivoted at their middle point on fulcrums which are secured to the vertical supports or partitions, 69, 69', 69'', etc., in front of the solenoids to which they belong, as is clearly shown in Figure 2 and Figure 3. The lower key wires are similarly controlled by the batteries of solenoids located beneath the key wire case. This method of connecting the various solenoids and levers to the key wires is preferable for the present purpose, but I do not wish to be restricted to this system alone, as it may be varied in several ways and I especially reserve the right to interchange the position of the solenoids and levers on the vertical partitions or supports, 69, 69', 69'', etc., so that the solenoids or magnets will be in front of the levers and thus when the said solenoids act on their levers they will cause them to withdraw the keys from over the punches and unlock instead of lock the punches, as this is of advantage for some purposes. Each of the solenoids, 11, 11', 11'', etc., is wired up in an electric circuit

similar to that illustrated in Figure 4 and hereinafter described and explained.

In the end of the key wire chamber back of the rear support of the key wires, is a sliding frame, 70, capable of moving back and forth a distance sufficient to withdraw the locking keys, 16, 16', 16'', etc., from their forward positions and thus unlock the punches. This sliding frame, 70, carries a series of vertical rods, 71, equal in number to the vertical layers of key wires, and spaced to correspond each with one of said layers. 71 is actuated at proper intervals by the lever, 66, acting on link, 68, so as to release all punches after each perforation. 80

The rear end of the key wire chamber forms a nest or space for the reception of the contact needle box, 5, a variety of which may be used as well as other contact devices. For facility in interchanging needle boxes or contact devices a group, 72, of binding posts is provided permanently connected by suitable wires to conductive plug wires, 7, 7', 7'', etc., so that when it is necessary to change from one contact device to another it is only necessary to disconnect the wires of said contact device from these binding posts, loosen the set screws, 124, and withdraw the box from the nest. The other box may then be inserted, clamped in by said set screws, and connected up to the plug wires, 7, 7', 7'', etc., by the binding posts, 72.

Various needle contact boxes may be required by differences in the size of master cards or variations in the arrangement of the data spaces of different types of master cards. The needle box, 5, shown in Figure 8 and Figure 9, is of a general type that may be varied to meet any of the requirements above noted. In the needle box, 5, the arrangement of needles indicated is purely arbitrary and may be varied in any way. Figure 8 shows the contact board, 73, forming the face of the box through which the needles, 6, 6', 6'', etc., project and against which the master cards are pressed by the feeding prism, 2, in making contact.

Each of these contact needles, 6, 6', 6'', etc., is yieldingly mounted in an electrically conductive tube, 74, supported and securely held by the contact board, 73, and a similar board or partition, 75, fixed in the frame of the box at a distance behind the face, 73. These boards, 73 and 75, are of non-conductive material so as to insulate the needles from each other. The needles also pass through holes in a third board, 76, of non-conductive material located behind and parallel to 75 and similarly secured in the frame, 5, of the needle box. Surrounding each contact needle and acting expansively between a collar, 77, on the needle and the partition, 76, is a coiled spring, 80, which presses the needle outward. The distance to which these springs, 80, can press the nee- 130

dles is limited by a short pin, 78, extending out of one side of the needle and traveling in a slot, 79, in the tube, 74. The outward movement of the needle being stopped when 5 the pin reaches the end of the slot, 79, as indicated in Figure 9. These slots are of such length as to allow the ends of the needles to all extend a suitable, uniform distance out beyond the surface of the contact board, 73. 10 The rear side of the needle box is closed by an electrically conductive plate, 23, located just beyond the rear end of the contact needles when they are in their normal position, but which these needles enter and make contact with when they are pushed back into the 15 face of the contact board against the action of their springs. Each of the conductive tubes, 74, in which the needles slide, is connected to a short, conducting wire extending 20 downward and passing through an opening in the bottom of the needle box and terminating in a clip for convenience in connecting the said wires to the binding post, 72, of the plug wires leading to and cooperating 25 with the plug or transfer board.

To accomplish certain ends previously referred to and more fully described herein-after, it is of advantage to be able, when necessary, to have means whereby any 30 needle or any number of the needles may be held in a more advanced position than normal, so that its end shall in such position extend further out in front of the contact board than the other or normally held needles, as shown in 6' and 6", Figure 9. To accomplish this each of the conductive tubes, 74, has a slot, 81, extending longitudinally from its inner end and on its opposite side from the slot, 79, before referred to. This 35 slot, 81, is longer than the opposite slot, 79, by an amount equal to the extra distance it is desired to have the contact needle extend beyond its fellows in their normal position. When any one of the needles is to be changed 40 from its normal position to its advanced position, it is only necessary by means of a plier or a suitable key to press it back against the spring far enough so that the pin, 78, is pushed clear out of the slot, 79, 45 and beyond the inner end of the tubes, 74. The pin is then turned half way around until it meets the longer slot, 81, which will allow the spring, 80, to open wider and extend the needle out further into the desired 50 position.

Figure 10 shows a front elevation and Figure 11 an end view of another form of a contacting device in position in the machine, where it may replace the contact 55 needle box hereinbefore described, when the machine is to be adapted to work with a movable, electrically conductive pattern, in the production of loom cards. This device consists of a series of movable, electrically conductive styles of fingers, 82, equal in num-

ber to the punches, mounted in a horizontal row, in a long extension, 84, across the frame, 83, and extending beyond its ends. This frame enters the nest or chamber of the machine and is held therein and connected 70 up in the same manner as the contact box previously described.

When this form of punch selecting control is used, the feeding prism, 2, and its supporting frame, 34, hereinbefore described, are removed from the machine and the conductive pattern is located on a cylinder indicated by 85 but not fully shown in Figure 11, or by other means such as those commonly used in the loom card punching art for the supporting and moving of the controlling pattern. This pattern cylinder may be revolvably mounted in a pair of supports forming part of and extending 80 back from either end of the extension, 84, or in a special frame rigidly secured in the ways on the machine from which frame, 34, has been removed, and may be moved or fed under the styles, 82, by mechanism connecting it with suitable movable parts of the 85 machine but not shown in this embodiment. The styles or fingers, 82, are of the shape shown in Figure 11, the circular end of each being fitted into and capable of vibrating 90 in a conductive plate, 88, of the same thickness as the finger. Flat springs, 87, one end of which is held in a slit in the end of the finger and the other in the plate, 88, as shown in Figure 11, keep the outer end of the fingers down against the pattern and 95 allow them to yield to inequalities therein. The plates, 88, are insulated from each other by sheets or plates of insulation, 86, placed between them and from the frame, 84, by insulating plates, 89, so that the 100 styles are completely insulated from each other. Each plate, 88, is provided with a conductive wire extending down to the bottom of a supporting frame and provided with a clip by means of which they are each 105 connected to its proper binding post in the group of posts, 72.

In Figure 4, 1 represents a perforated master card placed against a movable, electrically conductive plate, 2, which is connected by a conducting wire, 3, and switch, 22, to a source of electricity, 4. The conductive plate, 2, is capable of pressing the card, 1, up against the non-conductive support, 73, in which is yieldingly mounted the contact needle, 6. This needle, 6, is connected by a conducting plug-wire, 7, whose plug may be placed in any hole, 8, of a plurality of holes in the transfer or switchboard, 9, 115 which is wired by 10 to one end of the winding of an electromagnet, 11. The other end of the magnet winding being connected to the source of electricity, 4, by the wire, 12. The armature, 13, of the magnet, 11, is connected to one end of a lever, 14, the other end 120 125 130

of which is connected to a key wire, 15, controlling a key, 16, sliding in a support, 17, and capable of sliding over and locking the punch, 18, or being withdrawn so as to leave the 5 punch, 18, free to move up and down past the end of 16. When the key, 16, is thrust outward by the lever, 14, the punch, 18, abuts against it and is locked so that a card, 19, placed on the die, 20, is perforated by the punch as 10 the die, 20, is forced up and carries the card with it. Normally the position of the lever is vertical with the key withdrawn and the punch unlocked, as shown by the lever 14^A and its key 16^A and its punch 18^A, being 15 withdrawn from its locking position and brought to this normal position at the end of each cycle of operations by a movable rod, 71, through a loop in the end of the key wire. The same mechanism that oscillates 20 the rod, 71, also oscillates a plate, 21, through which the punch is passed to bring such of them as have been pushed up back to their normal position.

From the foregoing description it will be 25 seen we have an electric circuit embracing a source of electricity, 4, a movable, conductive plate, 2, an electromagnet, 11, controlling a punch, 18, and passing through a transfer or switchboard, 9, at the plug receiving hole, 8, where connection is made with the plug wire, 7, the contact needle, 6, whose plug fits into said hole, 8, said needle being opposite the contact plate, 2, where the circuit may be intermittently opened and closed, as 30 35 the plate moves up into contact with the needle or recedes therefrom. When the card is properly placed on the plate, 2, and carried up against the needle if there is a perforation in the card at a point opposite 40 the needle it will pass through the opening in the card, make contact with the plate, 2, and close the circuit above described, thus energizing the magnet, 11, which by attracting its armature, 13, throws the lever, 14, 45 which moves the key, 16, out into the locking position over the punch, 18, which abuts against it and is forced through the card, 19, as the die, 20, carries it up against the punch.

50 If there is no hole in the card at the point opposite the needle, this yieldingly mounted needle will be pushed back as the card advances, thus preventing the closing of the circuit so that no hole will be punched. It 55 is obvious that the contact needle, 6, could be made to control any other punch in the gang of punches by simply removing the plug of wire, 7, from the hole, 8, of the transfer board, 9, and placing it in the hole to 60 which the magnet controlling the desired punch is wired. Also, that the needle, 6, may be made to control a plurality of punches by connecting a plurality of plugs to the wire, 7. It is also evident that the 65 needle may be rendered neutral or inopera-

tive if the wire, 7, is left out of communication with the transfer board altogether.

The foregoing description shows how the simplest and most direct object of the invention is accomplished. It may, however, be 70 desired to punch the complement or inverse of the master card, that is, a card having all possible holes except the holes in the master card. In this case the circuit is switched from the contact plate, 2, by the switch, 22, to a similar but stationary conductive plate, 23, located at a suitable distance from the opposite end of the contact needle, 6, when the latter is in its normal position, so that 75 when the needle is pressed back by a card, 1, on plate, 2, it makes contact at its opposite end on plate, 23, all the rest of the circuit remaining as before described. In this case when a master card having no perforation 80 opposite needle, 6, is placed on the approaching plate, 2, it will meet the needle and press it back into plate, 23, thus closing the circuit through this plate, the switch, 22, and the rest of the circuit as before described, 85 energizing the magnet, 11, and causing a hole to be punched in card, 19, even though there is no corresponding hole in the controlling master card. In the case where 90 there is a hole opposite needle, 6, in the card, 1, said needle will pass through the 95 opening a distance sufficient to prevent its being pressed back far enough to make contact with plate, 23, and no hole will be punched since plate, 2, is not in circuit.

If for any reason it is desired to skip or 100 avoid punching a card corresponding to a master card containing holes in certain specified positions, it is only necessary to bring the contact needles of these particular positions further out of the contact needle box, 105 as illustrated by needle, 6^A, by simple means hereinbefore described, so that they meet the advancing master card, 1, before the remainder of the needles, which remain in 110 their normal positions, and to remove the plugs of the displaced needles from the transfer board, 9, and plug them in any holes in an auxiliary plug plate, 24, as illustrated by the plug wire, 7^A, corresponding to 115 contact needle, 6^A, and to close the normally open switch, 25, so as to bring in the magnet, 26, controlling the switch, 27, and the auxiliary plug plate, 24, whose holes are all in electrical connection and which is connected to the magnet, 26, by the wire, 28. We have 120 now, the switch, 22, being shifted so as to leave the conductive plate, 23, out of circuit, and bring the plate, 2, in the same circuit as was first described, and in addition thereto the secondary circuit brought in by the 125 means just indicated, that is, a circuit including plate, 2, the source, 4, the switch breaking relay, 26, the plug plate, 24, and the advanced contact needle, 6^A, which is 130 out of guard to prevent any card being

- punched under the influence of a master card with a perforation corresponding to the position of 6^a. When any master card, 1, is advanced by plate, 2, if there is a perforation opposite the position of the advanced needle, it will pass through and make contact with the advancing plate, 2, close the auxiliary circuit embracing the circuit breaker, 26, and plug plate, 24, thus energizing the circuit breaker to open the switch, 27, and break all the circuits of the machine before the master card has met any of the normally placed contact needles, and none of the punches will function. If on the contrary there is no hole 15 in the master card opposite the needle, 6^a, said needle will be pushed back by the card, thus preventing the closure of the contact breaking circuit, and the advancing master card finally meeting the normally positioned contact needles, the machine functions under the influence of its perforations through the chief circuits of the machine as before described.
- The means for automatically shifting the circuit by the switch, 22, to alternate between the movable plate, 2, and the fixed plate 23, are shown in Figure 5, where the switch 22 which is diagrammatically indicated in Fig. 4, is shown as a three-armed 20 switch attached to a six-toothed ratchet, 114, and supported in proper position beside the sliding frame, 34, by a bracket, 116, in which it may revolve when acted upon by the pawl, 115, pivoted to the frame, 34, as shown.
- This pawl is carried back by the frame as it intermittently recedes from the machine and on its return trip engages with a tooth of the said ratchet and revolves it and the three arms of the switch, 22, through an angle of 25 60 degrees. The movable plate, 2, diagrammatically shown in Figure 4, typifies any of the faces of the revolvable prism in Figure 5. These faces have electric communication with the switch, 22, by a tongue, 117, which is in sliding communication with the prism, 2, and extends through an opening of the side of the slide, 34, both the tongue and prism being suitably insulated from the slide. Means for electrical communication 30 between the plate, 23, and the switch, 22, are provided by a suitable conductive plug, 118, carried by the frame, 34, but insulated from it. It is evident from the above description that the revolving motion communicated to the ratchet by the oscillation of the frame, 34, causes the circuit to alternate between the movable faces of the prism and the fixed plate, 23.
- After the circuit has been broken by the 35 relay, 26, acting on the switch, 27, as hereinbefore described, the slide, 34, continues on its inward movement, carrying the pivoted trigger, 119, back so that its lower end meets and slides over the upper end of the switch, 27, and drops down in front of it. As the slide next recedes from its inner position, the trigger meets the upper end of the switch, which it just previously swung over, and carries it away from its open position. The end of the switch sinks down as it moves in 40 its arc until just as it reaches the position in which it closes the circuits, it slips from under the trigger which continues on in its movement with the frame, 34.
- A side elevation of the mechanism for automatically handling the cards to be punched, both before and after punching, and for feeding them to the punches, is shown in Figure 6, and a plan of the same in Figure 7. In these views 58 represents 45 the receptacle or magazine in which the cards are placed before perforation. The horizontal dimensions of this container are just sufficient to fit the cards and its bottom has an opening through the middle of 50 a width sufficient to allow the card pusher, 91, to pass through, the cards resting on the portions of the bottom on either side of this opening. Extending across the lower extremity of the side next the punches, and 55 opening just under the lip, 58^a, is a narrow slit or orifice just wide enough to admit the passage of a card. This magazine is supported on a frame, 57, which is firmly secured to and extends out in front of the 60 bolster, 54, at the top of the ram, 53, its inner end extending over the bolster and abutting against the die, 55. In the opposite faces of the opening of this frame, and extending longitudinally are two sets of ways, 65 in the lower of which is mounted the sliding member, 90, in which is pivoted the card pusher, 91. The said sliding member is reciprocated to and from the die, 55, by the action of the cam-groove, 61, and slide, 62, 70 Figure 1, acting through connecting rod, 63, the oscillating arm, 64, and link, 65. In the upper ways immediately above 90, which extend beyond the inner end of frame, 57, and clear across between the die, 55, and stripper, 75 56, to behind the rearmost side of the gang of punches, is mounted card carrier 92, for carrying the cards from the magazine, 58, immediately under which it moves and placing them in position for perforation. This card carrier, 92, is actuated from the motion of the slide, 90, hereinbefore described, through the medium of the two pieces, 90^a and 90^b, secured to the top of 90, and acting on two pairs of lugs extending in from 80 the opposite side of the card carrier, 92. In Figure 7 these parts, 90^a and 90^b, are shown acting on the lugs which pull card carrier 92 from under the punches, the sliding member, 90, being there shown in its extreme 85 outer position, while in Figure 7^a the pieces 90^a and 90^b are shown acting on the other pair of lugs used in pushing the card carrier, 92, under the punches. The distance through which the member, 90, and the card pusher, 95

91, which it carries, is moved in any stroke, is greater than that which the carrier, 92, travels, by an amount D, which is just sufficient to allow the card pusher, 91, to be 5 out in front of the magazine, 58, in position suitable for engaging with the outer edge of a card when the rear end of the carrier, 92, which is grooved as indicated at 92^A, is at rest in front of the magazine 10 in suitable position to receive the forward edge of the card into this groove as it is pushed from the bottom of the magazine by the pusher 91. As the card issues from the slit in the side of the magazine, it meets and 15 is guided by the lip, 58^A, before referred to, into the slot, 92^A, after traveling through the distance, D. Pivoted in the stripper, 56, and extending toward the magazine are two bent fingers, 94, one near either end of the lip, 20 58^A, so located and arranged as to be lifted by 92 when in its receiving position, as indicated in Figure 6, but which spring down when 92 recedes from its position and press against the card as it is being pushed under 25 the punches. Just as the card reaches the perforating position, its outer or pushed edge passes under these fingers and they spring down in front of it in position to guide the card into the chute, 60, leading to 30 the receiving magazine, 59, as it is withdrawn after perforation. As the cards issue from the chute they are received by the prongs, 95, pivoted at 96. These prongs vibrate at proper periods to carry the card up 35 and press it into the receiving magazine, 59, as illustrated in Figure 1, where the prongs, 95, are shown pressing a card previously received into the stack against the action of presser plate, 97, which holds the 40 stack in position and gradually recedes as the stack grows. The construction and action of this pressing feature of the mechanism of the magazine are very clearly shown in Figure 1 and Figure 6. The cards are prevented from being ejected from the magazine 45 when the prongs retreat by a pair of knife edged projections, 98, opposite each other on the inner sides of the magazine, behind which the ends of the cards snap as 50 they are pressed therein by the prongs, 95. The prongs are brought to their open or inclined position by a spring not shown, and receive their closing movement to press the cards into the stack by the motion of the 55 ram, 53, as it moves up in the act of perforating the cards. This motion of the ram is communicated to the prongs by link, 99, pivoted to the bolster, 54, and acting through the levers, 100 and 101, a slot in the bottom 60 of the link being arranged so that the levers are acted upon by the link during only a fraction of the stroke of the ram. The complete cycle of operation of this feeding and 65 ejecting mechanism is as follows: The ram, 53, being down, the card pusher, 91, being just in front of the outer edge of the bottom card in the magazine, 58, the sliding member, 90, being in its outermost position, and the rear end of the card carrier, 92, just under the edge of the guiding lip, 58^A, as 70 shown in Figure 6, the motion is started by the cam-groove, 61, acting through the mechanism hereinbefore indicated, and the sliding member, 90, moves toward the magazine, 58. At the beginning of this motion, the pusher, 75 91, meets the edge of the lower card in the magazine and pushes it through the orifice under the lip, 58^A, which guides it down to the slot, 92^A, in the carrier, 92, which remains motionless until just as the edge of 80 the card enters the slot, the parts 90^A and 90^B, which have left the outer pair of lugs on 92, meet the inner pair and thereby start the carrier, 92, to move back over the die, the pusher, 91, moving the card, and the 85 parts 90^A and 90^B moving the carrier, 92, so that they travel together over the die, 55. The displacement of 92 having released the fingers, 94, they spring down on the card and 90 slip over it and down in front of its outer edge as it approaches the position of rest for perforation. When the card reaches its final position, a long dwell in the cam-groove, 61, allows it to remain stationary a 95 sufficient time for the ram to complete the upward motion necessary for perforation and to start down again sufficiently to clear the punches before the retreating member, 90, carries the parts, 90^A and 90^B, back 100 against the outer pair of lugs and starts the carrier forward to eject the card just perforated. Just as the ram approaches its highest position in the act of perforating, the prongs, 95, are actuated by the link, 99, and levers, 100 and 101, as before indicated, 105 and the card previously perforated is snapped into the magazine, 59. As the ram sinks to its lower position a fraction of the motion is sufficient to release the levers, 100 and 101, so that the spring returns the prongs 110 to their open position ready to receive the card as it is carried down the chute. 115 The details of the interior of the prism of the rear feeding mechanism, consisting of the means for controlling the pneumatic features used in holding the card against the prism, are shown in Figure 12, which is an elevation of one of the rectangular faces cut away so as to show the valves and means for controlling them. The section shown in Figure 13 by plane x-x, Figure 12, perpendicular to the axis, showing the valves and interior chambers. This prism is mounted in the sliding frame, 34. The faces of the prism are all electrically conductive and provided with suitable means for most effectively making contact with the selective needles of the machine. A 120 suitable space in the middle of the interior, enclosed by the walls or partitions, 102 and 125 130

103, located at a distance from the ends of the prisms, is subdivided into five pneumatic chambers. The central interior chamber, *c*, from which the air may be exhausted through a pipe passing from the end of this cylindrical chamber, *c*, and through the wall, 102, and the adjacent trunnion, and opening into a hose, 130, at the gland nipple, 105, through which the air may be drawn by an air pump or other exhausting means suitably located, and four outer chambers, *C*¹, *C*², *C*³ and *C*⁴, separated from each other by the radial walls, 104, and enclosed also by the walls, 105, parallel to the outer faces of the prism, as shown in Figure 13. Free passage of air to these outer chambers is permitted by the short tubes, 106, which pass through the walls, 105, and the outer faces of the prism, in suitable positions to avoid the contact points in the faces of the prism. Each of the outer chambers communicate with the central chamber by valves, 107, slidingly mounted in ways and pressed down toward their seats by coiled springs as shown. These valves, 107, are opened against the action of their springs by rods, 108. These rods slide through holes in the frames in which the valves are mounted, passing also through slots in the valve stems and through openings in the wall, 102, at which points they support other valves, 109, whose seats are formed in these openings in the wall, 102, and extend from them on through holes in the end of the prism beyond which they project a suitable distance and end in rounded buttons or heads, 112, as shown in Figure 12. At the inner ends where they slide through the valve stem and support, these rods, 108, are provided with keys or feathers, 110, whose ends form inclined planes where they enter the valve stems. Around each rod is a coiled spring, 111, acting expansively between the valves, 109, and the adjacent supports of the valves, 107. These springs act to press the valves, 109, into their seats in the wall of 102 and at the same time by drawing the inclined feathers, 110, into the slots in the stems of valves 107, raise these valves from their seats and allow communication between the central chamber, *c*, and the outer chambers, *C*¹, *C*², etc. The rounded heads, 112, will then be in their outermost position. This is the normal condition, the valves, 107, being normally opened, and 109 being normally closed. As the prism, 2, is turned on its trunnion, and the heads, 112, on the rods which control the valves, approach the lowest point in their revolution, they successively meet the cam, 113, which is adjustably secured to an extension projecting down on the frame, 34.

As the head on the particular rod which controls the valve of the chamber which is

approaching the lowest position, meets the cam it is forced in against the spring, 111, so as to open the valve, 109, and at the same time push the feather, 110, out of the stem of 107, and this valve is closed, thus cutting off this lowest chamber off from the central suction chamber and allowing air to enter it through valve 109. From the foregoing description it will be seen that when the means for exhausting the air act through a hose, 130, the air is withdrawn from the central chamber, *c*, and also through the open valves from the outer chambers, *C*¹, *C*², *C*³ and *C*⁴, thus causing the air to flow into these outer chambers through tubes 106, opening into the faces of the prism. Suction is thereby created at these openings in the prism faces and as the latter are pressed against the cards in the magazines, 46, as before described, the cards are sucked up against and held pneumatically in suitable position on the prism faces, to be pressed against the contact needles. As the card recedes from the contact board after having met it, the prism revolves as hereinbefore indicated, so that the card last operating on the needles approaches the horizontal on the lower face of the prism. During this motion the head, 112, on the rod, 108, controlling the valve of the suction chamber behind the card, approaches and meets the cam, 113, and the rod is forced in so that during the motion the valve, 107, is closed and the valve, 109, open, thus cutting off the suction and admitting air to the chamber so that the card is released at the same time as its projecting edge meets a suitably formed extension, 121, Figure 14, on the rear side of the vertical receptacle, 120, into which the cards are discharged from the prism, as is clearly shown in the drawing, Fig. 14.

The method of operation of the various individual mechanisms which, in combination constitute the invention as a whole, have for clearness and convenience been hereinbefore indicated in connection with their foregoing detailed descriptions. Owing to its wide range and the various arts in which it may be used, the invention as a whole may be operated in several ways according to the nature of the work required of it. Three principal methods of operating the present embodiment will be described, the capacity for variation in each of which will be understood when taken in connection with the method of operation of the individual features hereinbefore given. 1st—It may be operated under the continuous attendance of an operative, whose duties consist in properly inserting the plugs at the transfer or switchboard so as to select and lock the proper punches to conform to the requirements of a written record or drawn pattern under the eye of the operative. This is the

method used in producing master cards. 2nd—It may be made to operate entirely automatically under the selective influence of perforated master cards with only occasional attendance, in which case one operative is sufficient to attend a plurality of machines. 3rd—It may be made to operate automatically under the selective influence of a movable pattern, whose surface consists of electrically conductive portions and non-conductive portions. In the tabulating art the data will often be gathered from its original source and registered on sheets or cards in written form instead of being perforated on printed cards. Also, in the production of jacquard cards the original ornamental designs are drawn or painted and from these as guides cards are suitably perforated to conform to the design and these cards are used subsequently in the production of duplicates. When the invention is used for this kind of work no master cards are used, the selective capacity of the machine being governed by the operative working at the transfer board with the plugs. In this case the plugs are first all removed from the board. The plugs and holes are numbered or otherwise marked or named according to a scheme or system understood by the operative and forming an index of the relation between various items of data and the positions they are to occupy on the perforated tabulating cards, or in the case of jacquard cards a relation between the pictured design and the required holes in the master card to be punched. After all communication between the selective needles and the solenoids has been broken by the removal of the plugs, the data sheet or pictured design, as the case may be, is consulted and certain plugs as indicated thereby are inserted in their proper holes by the operative, thus connecting the necessary solenoids in operative condition to lock the proper punches. After the requirements of the particular data sheet or textile design are exhausted, no other plugs are inserted, so that all circuits except the required ones remain open and the machine is now in condition to punch all the required holes in a card inserted under the punches. If the machine is now started, a card will automatically be fed to the punches by the forward feeding mechanism. A face of the conductive prism will be pressed against the conductive needles, thus closing the circuits which have been plugged in and locking the corresponding punches. The ram now being forced up perforates the card, which is then automatically withdrawn by the card handling mechanism, all of which operation has been hereinbefore described in detail. From the above description it will be seen that the operative has opportunity to insure accuracy by revising or verifying his work at

the plug board before punching the card. It is also obvious that the time required to read and plug in the pattern is very considerably longer than that required for the machine to punch the card, which only requires a fraction of a second. In order to obviate the necessity of the machine standing inoperative during the considerable periods of time required for the plugging in of the pattern, a plurality of plug or switch boards may be wired up to the machine in addition to the one built into it, and at a distance from it, so that two or more operatives may be simultaneously employed in plugging patterns or data. These boards may be placed in any suitable location and positioned either vertically or horizontally in the form of a desk or table for the convenience of the operative. The various wires of each of the sets of plugs corresponding to the respective boards may all be brought together in the form of a cable where they approach the machine and suitable means provided for switching them in and out of the circuit altogether at a convenient point therein. During the time the operative is engaged in plugging in a pattern his set of plug wires will be switched off the machine so that the machine may be used by others. In the second method of operation, namely, where the machine operates under the selective influence of a perforated master card, the stack of influencing master cards which have been previously perforated either by the machine itself, as hereinbefore described, in the first method, or in any other way, is placed in the magazine, 46, at the rear of the machine, and a corresponding stack of blank cards to be perforated under the selective influence of said master card, is placed in the magazine, 58, of the punch feeding mechanism. A contact needle box suitable for the particular work in hand being placed in the chamber of the machine and any needle adjustments, if such are called for, being made in the manner hereinbefore described. The plugs are then inserted in the switchboard in the particular arrangement called for by the nature of the work being performed. After the machine is thus set up and started, its operation is entirely automatic. The rear feeding mechanism applying the master cards successively against the contact needles and then discharging them into the magazine, 120. Simultaneously with the approach of a master card to the contact needles at the rear of the machine, a blank card is removed from its magazine, 58, by the forward feeding mechanism and suitably placed under the punches, as hereinbefore described. When the master card is pressed up against the needles it acts selectively on them in accordance with the location or arrangement of its perforations, allowing 120

the necessary electrical contacts to energize those magnets which will lock the proper punches and preventing all others. The ram, 53, then ascends and perforates the 5 blank card, which afterwards is withdrawn and placed in the magazine, 59, as the ram descends. The whole operation being entirely automatic so that only occasional attendance is required.

10 The third method of operation is that in which the means of influence for selectively locking the punches is a movable pattern, portions of whose surface are electrically conductive and other portions non-conductive. This is a pattern method commonly used in the production of jacquard cards, and the means of applying the pattern to and feeding it under the contact styles are not specially described as no originality is 15 claimed in these features, any of those in common use being available, it being merely here desired to show that the invention may be readily adapted to such pattern means. In this method of operation the rear magazine and master card feeding device are removed and replaced by a revolving cylinder, as hereinbefore indicated, and the contact styles shown in Figure 10 are placed 20 in the chamber of the machine. The cards to be perforated are as before placed in the forward magazine, 58, and fed to the punches as in the previous methods of operation. In this method the action of the machine is completely automatic and similar 25 to that of the second method of operation except in the difference of the selective influencing means as above indicated.

30 The invention herein set forth may also be used to directly control the needles of a jacquard mechanism while weaving in the same manner as it locks punches for punching cards, and I reserve the right to make such application of it.

35 What I do claim as my invention and desire to secure by Letters Patent is:—

1. In a card punching machine, the combination of a gang of punches and co-operating mechanism, keys for locking the punches, electromagnetic means for operating said 40 keys, conductive contact needles for selectively controlling said electromagnets, movable conductive plate co-operating with said needles to make contact, pattern means acting between and limiting the extent of the 45 electrical contact of said plate with said needles, means for interchanging the said needles among the said magnets.

2. In a machine of the character specified 50 the combination of a plurality of punches and co-operating perforating mechanism, means for locking and unlocking the punches individually, electromagnetic means for individually actuating the punch locking means 55 to lock the punches in operative position, means for selectively energizing the units

of the magnetic control of the punch locking means automatically, means for interchanging the units of said selective energizing means among the units of said magnetic actuating means so that any unit of the 60 former may be made to control any unit of the latter, means for automatically feeding blanks to the punching mechanism, means for removing and receiving blanks from punches after perforation. 75

3. In a machine of the character specified, the combination of a plurality of punches and co-operating punching mechanism, means for locking and unlocking the punches individually, electromagnetic 80 means for individually actuating the said punch locking means for locking the punches in operative position, means for selectively energizing the different units of the said magnetic means under the selective influence of perforated master or pattern cards, means for automatically applying said perforated pattern cards so as to suitably influence the operation of the said magnetic means to lock the proper punches 85 and prevent the locking of any others in any given case, means for interchanging the units of the said selectively energizing means among the units of said magnetic actuating means so that any unit of the 90 former may be made to control any unit of the latter, means for automatically feeding blanks to the punches and withdrawing same therefrom after perforation. 95

4. In a machine of the character specified 100 the combination of a gang of punches and co-operating punching mechanism, means for locking and unlocking the punches, electromagnetic means for individually actuating the said punch locking means, means for selectively energizing the various units of the said magnetic means through the selective skill of an operative, means for simultaneously performing a card by the punches selectively locked, means for automatically feeding cards to the punching mechanism and removing them therefrom after perforation, means for automatically stacking the cards as they are discharged from the 105 machine. 110

5. In a machine of the character specified 115 a plurality of punches and co-operating punching mechanism, means for locking and unlocking the punches individually, electromagnetic means for actuating the said punch locking means so as to lock the punches in operative position, means for selectively energizing the various units of the said magnetic means under the selective influence of a pattern sheet or surface, means for interchanging the units of said selective energizing means among the units of said magnetic actuating means so that any unit of the former may be made to control any unit of the latter, means for auto- 120 125 130

- 5 matically feeding the blanks to the punching mechanism and withdrawing them therefrom after perforation, means for receiving and automatically stacking the cards after withdrawal from the machine.
6. In a punching machine the combination of a plurality of punches and co-operating punching mechanism, means for locking and unlocking the punches individually, electro-
10 magnetic means for individually actuating the punch locking means, a plurality of electrically conductive contact needles or other contact means, a movable, electrically conductive surface for making and breaking
15 contact with the needles to intermittently energize the punch locking means, a pattern means for selectively influencing the extent or method of contact between the said needles and said surface, an electric
20 circuit embracing the contact needles, the electromagnets of the punch locking means and the movable conductive surface, means for changing the electric circuits between any contact needle and any electromagnet
25 of the punch locking means from the given electromagnet to any other electromagnet of the punch locking means, means for breaking the electric circuit between any contact needle and the electromagnet of the
30 punch locking means which it controls, means for moving the conductive contact surface plate relatively to the contact needles, means for automatically feeding cards to the punches, means for automatically
35 withdrawing cards from the punches after perforation.
7. In a machine of the character specified the combination of a plurality of punches and co-operating punching mecha-
40 nism, means for locking and unlocking the punches individually, electromagnetic means for individually actuating the punch locking means, a plurality of conductive contact needles, a movable, electrically con-
45 ductive surface for making and breaking the contact with said needles intermittently, pattern means for selectively determining the extent of contact between said needles and said surface, a plurality of similar
50 electric circuits, each consisting of suitable connections for and including a source of electricity, an electromagnet, one of the selective needles and the movable conductive surface, means for interchange so that any
55 contact needle may be changed from any given circuit to any other circuit of the said system of circuits, means for adapting any contact needle to control a plurality of magnets, means for taking any contact
60 needle out of circuit entirely, means for automatically changing the pattern or selective influencing means so that one pattern may follow another and successively influence the locking of different sets of
65 punches, means for automatically feeding

cards to the punching mechanism and withdrawing them therefrom after perforation.

8. In a machine of the character specified, the combination of a plurality of punches and co-operating punching mechanism, 70 means for locking and unlocking the punches, electromagnetic means for individually actuating the punch locking means, means for selectively energizing the different units of the said magnetic actuating means, means for interchanging the units of the said selective energizing means among the units of the said magnetic actuating means so that any unit of the former may be made to act on any unit of the latter, 80 means for suitably influencing the selective means to energize the corresponding magnetic control to lock the proper punches, means for automatically feeding cards to the punching mechanism and withdrawing them therefrom after perforation, means for automatically stacking the cards as they are discharged from the machine.

9. In a machine of the character specified the combination of a plurality of punches and co-operating perforating mechanism, means for individually unlocking the punches to place them in inoperative condition, a plurality of electromagnets or sole-
100 noids for actuating the punch controlling means individually, a plurality of contact styles or fingers yieldingly mounted parallel to and insulated from each other, a pattern sheet or surface, a plurality of similar electrically conductive circuits, each embrac-
105 ing through suitable connections a source of electricity the pattern surface one of the contact styles and one of the electromagnets, means of interchange whereby any one of the contact styles may be switched from the control of the electromagnet in any given circuit to the control of a similar magnet in any other circuit in the system of circuits, means for taking any contact style or finger out of circuit entirely, means for locking the 110 punches in operative condition, means for automatically feeding blanks to the punching mechanism and removing same there-
115 from after perforation.

10. In a machine of the character specified the combination of a gang of punches with co-operating punching mechanism, keys for locking the punches in operative positions with key wires attached to the keys for shifting them, said wires being regularly ar-
120 ranged in horizontal and vertical planes; a plurality of electromagnets equal in number to the key wires arranged and supported in groups or batteries in parallel vertical planes spaced at regular intervals along the key wires and perpendicular thereto, the individual magnets being located in the said groups or batteries in such relation to each other and to the key wires as to be in position to be most directly and compactly 125 130

coupled, each to its corresponding key wire with a minimum of intervening mechanism, a plurality of levers equal in number to the key wires, each lever being coupled at one end to the armature of a magnet and at the other end with the key wire corresponding to said magnet, said levers being of varying lengths to accommodate the different distances between the key wires and their corresponding magnets and fulcrumed so as to all have the same throw, a plurality of electrically conductive contact needles yieldingly mounted, a movable electrically conductive plate for making and breaking contact with said needles, means for moving said plate up against and away from said needles, a plurality of similar electric circuits, each embracing through suitable wiring a source of electricity the movable conductive plate one of the contact needles, one of the electromagnets and a switch or plug board, a plurality of plugs fitting suitable openings in said plug board, each plug being wired to one of the contact needles, means for unlocking the punches, means for automatically feeding perforated pattern cards to the movable conductive plate and removing them therefrom, means for automatically feeding blank cards to the punches and removing them therefrom after perforation, means for automatically receiving and stacking the cards as they are discharged from the machine.

11. In a card punching machine the combination of a plurality of punches and co-operating punching mechanism, keys equal in number to the punches for locking said punches in operative position, key wires attached to the keys and arranged parallel to each other in a series of parallel, horizontal planes vertically above each other, a plurality of electromagnets or solenoids equal in number to the keys and arranged in a series of batteries in parallel vertical planes perpendicular to the key wires and spaced at intervals along the key wires, the individual solenoids of any battery being connected each to its respective key wire in the horizontal plane of wires corresponding to the said battery, a plurality of levers, one end of each being connected to the armature of a magnet and the other end coupled to the key wire corresponding to said magnet, the levers being of varying lengths to accommodate the different distances between the magnets and their corresponding wires and so fulcrumed as to move the keys all the same distance when actuated by the magnet, a movable conductive plate or surface capable of accommodating a perforated pattern card, a plurality of electrically conductive contact needles yieldingly mounted parallel to and insulated from each other in a case or frame of such design as to be readily removed from the machine, means for replac-

ing one type of contact needles or styles by another of different type or capacity, means for moving the contact plate to co-operate with the contact needles intermittently, a switchboard and plugs, a plurality of similar electric circuits each embracing through suitable connections a source of electricity, the movable contact plate or surface, one of the openings of the plug or switchboard, one of the contact needles, a plug and one of the electromagnets, means for unlocking the punches, means for automatically feeding perforated pattern cards to the movable contact plate, means for automatically feeding blank cards to the punching mechanism. 80

12. In a card punching machine the combination of a plurality of punches and co-operating punching mechanism, means for locking the punches, a plurality of electromagnets suitably arranged and connected for actuating the punch locking means individually, a movable electrically conductive surface capable of suitably holding a master or pattern card or sheet, a plurality of electrically conductive contact needles yieldingly mounted in a case, box or frame parallel to and insulated from each other in said case or frame and with their forward ends projecting a uniform distance out from their support in a position to co-operate with the movable conductive plate, a fixed conductive plate secured to the back of the said frame or box in which the selective needles are mounted in such position that the rear ends of the needles do not 100 meet the said fixed plate when in their normal position but so located that when the needles are pushed back by the master card as it is pressed up against their forward projecting ends, the rear ends of said needles 105 meet and make contact with the said fixed plate, a plurality of similar electric circuits, each embracing through suitable connections a source of electricity, one of the electromagnets, the movable conductive plate, one of the contact needles and a switchboard by means of which the various contact needles may be interchanged from one circuit to another, means for automatically switching the movable metallic plate out of circuit and re- 110 placing it therein by the fixed conductive plate. 115

13. In a machine of the character specified the combination of a plurality of punches, suitable die and co-operating punching mechanism, means for simultaneously locking the punches, a plurality of solenoids suitably arranged and connected for operating the punch locking means individually, a movable metallic plate or series of plates capable of suitably holding a perforated master or pattern card, a plurality of metallic selective contact needles yieldingly mounted in a box or frame, parallel to and insulated from each other,

- with ends projecting a uniform distance out from the box or case in position to meet and co-operate with the movable metallic plate or plates and the cards carried thereby
- 5 when said cards approach and meet said needle, means for advancing the said needles a suitable distance longitudinally so that in their advanced position they project farther from their containing case and are met earlier on the approach of the movable plate and card than when in their normal positions, a switchboard and plugs for interchanging the contact needles between the various circuits and solenoids, a series of
- 10 similar primary electric circuits, each including through suitable connections a source of electricity, a selective contact needle, an opening in the switchboard, a plug, a solenoid and the movable, metallic plate, a
- 15 secondary or auxiliary circuit embracing through suitable connections the source of electricity, the movable, conductive plate, a switch which opens to break all circuits and a magnet capable of opening said switch,
- 20 a secondary switch or plug plate to which the conductive plugs of the advanced needles may be transferred from the primary board, means for automatically closing the said circuit breaking switch, means for automatically
- 25 moving the card carrying contact plate to and from the contact needles.
14. In a card punching machine the combination of a plurality of punches and co-operating punching mechanism, means for locking the punches individually, a plurality of electromagnets or solenoids for actuating the punch locking means to individually lock the punches in operative positions, a plurality of conductive needles or
- 30 styles for making suitable, electric contact so that each may thereby close an electric circuit to energize one of the said electromagnets, a movable, electrically conductive surface or plate suitable for co-operating
- 35 with the conductive needles so as to close electro circuits of the aforesaid electromagnets, a plurality of similar electric circuits, each embracing in suitable connections a source of electricity, the movable conductive surface, one of the contact needles and one of the electromagnets, means for interchanging the conductive needles among the various circuits of the aforesaid system of circuits so that any contact needle may be removed from the control of a given magnet and placed in control of any other magnet in the system, means for taking any contact needle or needles out of circuit so that any number
- 40 of punches may thereby be rendered inoperative during the functioning of the machine, a secondary or auxiliary electric circuit embracing the source of electricity, the movable conductive plate, a switch which
- 45 opens to break all circuits and an electro-
- magnet capable of opening said switch, a conductive plug plate by means of which any of the contact needles may be brought into the secondary circuit after being cut out of the aforesaid system of primary circuits, means for displacing the contact needles from their normal positions and so conditioning them as to make contact with the movable conductive plate in a manner suitable to close the secondary circuit, energize the aforesaid switch opening magnet and thereby break all circuits, means for automatically closing the said circuit breaking switch, pattern means for acting selectively between the contact needles and the movable conductive plate to allow the closing of suitable circuits to lock the punches proper in any given case and preventing all others.
- 50 15. In a card punching machine the combination of a plurality of punches and corresponding die with co-operating punching mechanism, keys and key wires corresponding in number to the punches, each key being suitably arranged to lock its corresponding punch, a plurality of solenoids, each of which is connected with a corresponding key to lock a punch, a plurality of metallic selective needles corresponding in number with the solenoids, a movable conductive plate, a perforated master card or other means of selectively influencing the punch locking solenoid through action on the needles automatically, a plurality of similar electric circuits equal in number to the solenoids formed of suitable conductors and properly arranged so as to each embrace a solenoid, a selective needle, the movable conductive plate and a source of electricity, means for interchanging the said contact needles between the various electric circuits of the system of said similar circuits so that any selective needle may be placed in circuit with any solenoid, means for leaving any needle or any solenoid out of circuit, means for automatically cutting the movable conductive plate out of the circuits and replacing it therein by a suitable fixed conductive plate, means for locking the punches, means for feeding cards to the machine automatically, means for discharging cards from the machine automatically.
- 55 16. In a card punching machine the combination of a gang of punches, a suitable die and co-operating punching mechanism, means for locking the punches, electromagnetic means for actuating the punch locking means, means for selectively energizing electromagnetic punch locking means, means for interchanging the units of the said selectively energizing means among the units of the said magnetic means, perforated pattern means for suitably influencing the selective means to energize the corresponding magnetic control, blank card feeding means embracing a frame extending hori-

zontally out in front of the bolster on the ram and abutting against the die, a card pusher pivoted to a sliding member movable in ways in said frame, means for reciprocating said sliding member to approach and recede from the die and punches, a card receptacle or magazine supported on said frame adjacent to the punches, a slideable card carrier or guide mounted in ways above the sliding member and actuated by said member to move in said ways immediately under the magazine to receive a card therefrom, guide said card between the punches and die and to withdraw it therefrom after perforation, a chute for guiding the card as it is discharged from the machine, means for receiving and stacking the cards automatically as they are discharged from the machine, all substantially as specified.

17. In a machine of the character specified the combination of a plurality of punches corresponding die and co-operating punching mechanism, means for locking and unlocking the punches, a plurality of electromagnets for actuating the said locking means, a plurality of conductive contact needles, a movable conductive contact plate co-operating with said needles, a perforated card for suitably influencing the nature and extent of the contact between said needles and said plate, a plurality of similar electric circuits, each embracing a source of electricity, the contact plate, one of the electromagnets and one of the contact needles, means for interchanging the needles among the various circuits, means for feeding cards to punching mechanism, means for perforation, means for receiving and stacking the cards as they are discharged from the machine after perforation, embracing a horizontal magazine or receptacle suitably located in front of the machine under the feeding mechanism with its open receiving end in proper relation to the chute thereof, a plurality of vibratory prongs or fingers for receiving the cards from the chute and pressing them into the magazine, a movable beam or arm passing slidably through an opening in the rear of the magazine and supporting a presser plate for maintaining the cards in a compact stack as they are received, suitable rollers and a rail for guiding said presser beam or arm and facilitating the free movement thereof, means for maintaining pressure on the arm and presser plate by the action of gravity, means for retaining the cards in the magazine against the action of the presser plate, means for communicating intermittent vibratory motion to the aforesaid prongs from the motion of the ram of the machine, all substantially as specified and for the purposes set forth.

18. In a machine of the character specified a plurality of punches and punch locking means, means for locking and unlocking the punches, a plurality of electromagnets for actuating the said locking means, a plurality of conductive contact needles, a movable conductive contact plate, a perforated card, a plurality of similar electric circuits each embracing a source of electricity, the contact plate, one of the electromagnets and one of the conductive needles, means for interchanging the needles among the various circuits, means for feeding the cards to the punching mechanism, means for receiving and stacking the cards as they are discharged from the punching mechanism, means for feeding the perforated master cards to the contact needles, embracing a revolvable square prism with rectangular, electrically conductive faces, a pneumatic chamber contiguous to each of the faces of the prism, with suitable openings for the passage of air through said face to said chamber, a valve for the intermittent admission of air through one end of said chamber, a central pneumatic chamber surrounded by the said face chambers, valves for controlling the intermittent passage of air from the outer or face chambers, to the central chamber, means for exhausting the air from the central chamber, means for supporting and controlling the valves, a cam secured to the prism support for co-operating with the valve controlling means for suitably actuating the valves through the motion of the prism as it rotates, means for reciprocating the prism between the card container or magazine and the contact needles, means for suitably revolving the prism as it recedes from the needles so as to successively bring each of the prism faces parallel to the contact needleboard, means for receiving the cards as they are discharged from the machine, all substantially as specified.

19. In a card punching machine the combination of a plurality of punches and co-operating punching mechanism, means for locking the punches, a plurality of electromagnets suitably connected with the punch locking means to control their operation, a plurality of conductive selective needles or styles yieldingly mounted and suitably insulated from each other, a plurality of movable contact surfaces for co-operating with said styles or needles, pattern means carried on the said movable contact surfaces to govern the extent and nature of the contact between said surfaces and said needles, a plurality of similar electric circuits each embracing a source of electricity, the movable contact surfaces, one of the contact needles, one of the electromagnets and a switchboard; a plurality of conductive plugs, each

wired to one of the contact needles or styles and fitting openings in the switchboard to close a circuit therewith, means for connecting any contact needle with a plurality of plugs so that the needle may control a plurality of magnets when said plugs are fitted into the switchboard.

In testimony whereof I have signed my name to this specification in the presence of two subscribing witnesses.

JAMES H. GAULT.
